UNITED STATES PATENT OFFICE.

JOSEPH L. DUGGAN, OF ELIZABETH, NEW JERSEY.

LAND AND WATER TOY.

Application filed April 8, 1925. Serial No. 21,647.

My invention relates to a toy adapted to be propelled on land or in water and the present invention is an improvement on the land and water toy forming the subject matter of Letters Patent No. 1,456,429, granted to me May 22, 1923.

The general object of the present invention is to improve the patented toy referred to in various particulars especially with respect to the means connecting the propelling mechanism with the figure simulating an oarsman and serving to give a lifting and rowing movement to the figure.

More specifically, the present invention has for an object to simplify the construction and to insure that the proper movements are imparted to the figure to simulate a rowing action.

Reference is to be had to the accompanying drawings forming a part of this specification, it being understood that the drawings are merely illustrative of one example of the invention.

Figure 1 is a view partly in side elevation and partly in vertical section of a toy embodying my invention showing in one position the figure representing an oarsman, the section being indicated by the line —1— in Figure 2;

Figure 2 is a plan view;

Figure 3 is a view similar to Figure 1 but showing the position of the figure after a partial rotary movement of the actuating element for the figure which is illustrated in the form of a crank shaft;

Figures 4 and 5 are fragmentary views in vertical section showing successive positions of the figure during a revolution of the actuating crank shaft, the housing for the propelling mechanism being omitted from said Figures 4 and 5;

Figure 6 is a sectional plan view of a ratchet and pawl assemblage forming part of the illustrated motor mechanism;

Figure 7 is a transverse vertical section in a plane indicated by the line 7—7, Figure 6.

In the illustrated example of my invention the numeral 10 indicates a boat body; 11, a pair of front running wheels on a driven axle 12; and 13 a rear wheel on the lower end of standard or spindle 14 having a laterally bent handle arm 15 at the upper end. Said wheel 13 may be employed as a steering wheel on land or as a rudder in the water. The numeral 16 indicates a figure

simulating an oarsman and 17 the oars operated by the movements of the figure; said oars being confined in oar locks 18 on the upper edge of the body 10.

60

The numeral 19 indicates the housing for the motor mechanism, said motor mechanism including a shaft 20 here shown as at a slight angle to a vertical line and having a winged winding bar 21. On shaft 20 is a bevel pinion 22 meshing with a smaller bevel pinion 23 (Figure 1) on axle 12. A spring 24 similar to a clock spring is secured at one end to shaft 20. The outer end of the spring is secured in the illustrated example 70 to a yoke 24 rigid with pinion 22. The arrangement is such that the reaction of spring 24 upon being wound by the winding shaft 20 will serve to turn the yoke 25 and pinion 22, the latter driving the pinion 23 and axle 75 12 and running wheels 11.

In accordance with the present invention the following means is provided to actuate the figure 16. A lever 26 here shown as having a slightly upturned front end 27 has an upwardly extending arm 28 thereon which is engaged in a keeper 29 on the figure 16 at the back. Said lever 26 extends rearwardly through a slot 30 in an extension 31 of housing 19. Said housing includes a top plate 32 held by tongues 33 to the sides of the boat body 10. The rear end of lever 26 is connected with the crank arm 34 of crank shaft 35, said shaft turning in bearings in side members 36 of the housing extension 31.

The figure 16, it will be observed, is jointed, the legs 116 being pivoted as at 216 to the torso of the figure, the arrangement being such that the feet 316 rest on the bottom 95 of the boat body 10. The lever 26, it is to be observed from various figures, rests on the bottom of the boat body 10, the bearing point being at the salient angle (126) 100 formed by the body of said lever 26 and the 126 of said lever constituting a fulcrum.

On the crank shaft 35 is a bevel pinion 37 here shown as a sprocket pinion engaging a barrel pinion 38 rigid with the driven pinion 23 whereby said crank shaft 35 is driven with the turning of said pinion 23.

With the described drive for the crank shaft and the employment of the lever 26 connecting the crank shaft with the figure 16 and resting on the bottom of the body at the point 126, the turning of the crank arm 110

34 with the revolution of the shaft 35 will move the figure 16 from the position indicated, for example, in Figure 1 successively to the positions of Figures 3, 4 and 5 so 5 that it will be seen that the figure moves from a rearwardly inclined position upwardly by lifting action of arm 28 and then forwardly to the position of Figure 3, then rearwardly to the position shown in Figure 10 4, thence to the position shown in Figure 5, for giving the proper movement to the oars 15 17 for propelling the boat.

The oars are shown as having at their inner ends eyes 117 held by pins 39 depending from the arms 40 of the figure 16.

Reverting to the motor mechanism the shaft 20 has fixed thereto a ratchet wheel 41 which is engaged by a spring pawl 42 integral with the top plate 32 of the housing 20 19 in a manner that the ratchet wheel 41 may turn with the winding shaft 20 and slip past the pawl 42 but said pawl will prevent retrograde movement of the ratchet wheel 41 and shaft 20, thereby requiring the 25 spring 40 to turn the yoke 25 and wheel 22.

A governor device is shown in the motor mechanism the same consisting of a wheel 43 and driven by the barrel pinion 38 and

meshing with a pinion 44 on a shaft 45, which shaft 45 has a blade 46 acting as a retarding fan. Said governor device forms no part of my invention. 20

I would state furthermore that while the illustrated example constitutes a practical embodiment of my invention, I do not limit myself strictly to the exact details herein illustrated, since, manifestly, the same can be considerably varied without departure from the spirit of the invention as defined in the appended claim. 35 40

Having thus described my invention, I claim:

In a toy of the class described, a body, motor driven traction wheels therefor, a figure in the body, an angular lever, the arms 45 of which define a corner resting on the bottom of the body, one end of said lever supporting said figure, means operated from the motor for actuating the lever to cause movement of the figure simulating the motions 50 of an oarsman, said means including a rotatable crank arm engaged with the end of the lever, operable to rock the same on its fulcrum and slide the same on the bottom. 50

JOSEPH L. DUGGAN.
